SPRINKLER SYSTEM CONNECTION FOR SPRINKLER HEAD

Herbert W. Hempel, Belleville, Ill.

Application July 27, 1953; Serial No. 370,457

4 Claims. (Cl. 210—532)

The present invention relates generally to fire protection systems, and more particularly to improved connections for the sprinkler heads for attaching the same into the fluid containing pipe line.

In the early years of fire protection sprinkler systems, the installations included standard reducer T's with pendant drop lines extending from the bottom thereof for the attachment of sprinkler heads. As the systems aged, it was found that rust, dirt, and other accumulations dropped into the pendant lines and fouled the sprinkler heads, making them inoperative. To overcome this situation, underwriters and other agencies now require that the stem of the standard T be directed upwardly from the fluid pipe line so that the sprinkler head is connected thereto by two vertical and one horizontal pipe line segments with the necessary elbows in order to dispose the sprinkler head in operative position beneath the fluid containing pipe line. Satisfactory results are obtained with this sprinkler head connection, but there are numerous disadvantages.

The installation is more expensive than the simple drop pendant, since more parts and more labor are required for installation. Additional pipe fitter's time is often required in making the connection installation, since often the headers are close to ceiling or roof joists, making it difficult to swing pipe wrenches in limited quarters. Additional points for possible leakage are included in this type of sprinkler head connection, particularly since often the parts cannot be effectively tightened in cramped quarters. In new installations when pendants are dropped through ceilings, a dummy drop pendant for ceiling mounted sprinkler heads is first used to permit completion of the ceiling job after which the pendant is measured for length, removed, rethreaded and re-installed with the sprinkler head attached. In this connection, frequently, when the pendant drop is to be removed, the multiple connection above the header tends to twist and it becomes very difficult to relocate the elbow into which the pendant must fit and square this pendant with the ceiling, particularly in areas where no access space is available.

Therefore, an object of the present invention is to provide a novel simple sprinkler head connection which will overcome all of the disadvantages inherent in presently employed T fittings, which will fully comply with the requirements of the underwriters in respect to elimination of fouling of the sprinkler head through the accumulation of foreign matter, and which will permit the sprinkler head to depend directly from the fluid pipe line in manner similar to original installations.

Briefly, one embodiment of the invention accomplishing these objects is a modified T fitting formed to include an internal water chamber having a connection at the top with the fluid pipe line and a connection at the bottom with the sprinkler head, the former being at a level adjacent the top of the fluid pipe line so that foreign matter passing through or surging back and forth in the fluid pipe line cannot enter the water cham-

ber and thence pass into and foul the sprinkler head. A second exemplification of the present invention comprises a modified T fitting which includes a riser extending vertically from the bottom of the T fitting to a point near the top of the fluid pipe line, the riser communicating with the fluid pipe line at the top and with the sprinkler head at the bottom.

Another object is to provide a novel sprinkler head connection which will facilitate the installation and removal of sprinkler heads, and which is economical both to make and to install.

Another object is to provide a novel sprinkler head connection which will prevent the fouling of the sprinkler head through the accumulation of foreign matter, and which will continue to function for its intended purpose without maintenance for an indefinite period of time.

The foregoing and other objects and advantages are apparent from the following description taken with the accompanying drawing, in which:

Fig. 1 is a side elevational view of a sprinkler head connection incorporating the teachings of the present invention installed in a fluid pipe line, only segments of the pipe line and of the depending straight run of pipe to the sprinkler head being illustrated for conservation of space;

Fig. 2 is an enlarged transverse vertical cross-sectional view on substantially the line 2—2 of Fig. 1;

Fig. 3 is a vertical longitudinal cross-sectional view on substantially the line 3—3 of Fig. 2;

Fig. 4 is a cross-sectional view similar to Fig. 2 through a modified sprinkler head connection; and

Fig. 5 is a vertical longitudinal cross-sectional view on substantially the line 5—5 of Fig. 4.

Referring to the drawing more particularly by reference numerals, 10 indicates generally one embodiment of a sprinkler head connection which includes the concepts of the present invention (Figs. 1-3). The connection 10 is a modified T fitting comprising a casing 12 having threaded annular aligned openings 14. Within the casing 12 is an annular wall 16 which, with the casing 12, forms a water chamber 18. An opening 20 in the wall 16 communicates the water chamber 18 with the interior of the casing 12, and a threaded opening 22 through the casing 12 communicates the water chamber 18 with the outside of the connection 10. The threaded opening 22 threadedly receives a depending pipe segment 24 to the lower end of which is connected a sprinkler head (not shown). The sprinkler head may be connected directly into the threaded opening 22 if desired for some installations. Pipe segments 26 of the main fluid pipe line are threaded into the openings 14 in the usual manner.

It will be noted that the opening 20, which may be of any configuration, is above the flow line of the pipe segments 26 so that rust and other foreign matter within the system will not enter the water chamber 18, hence, will not get into and foul the sprinkler head disposed beneath the opening 22. The size and shape of the water chamber 18 as defined by the casing 12 and the wall 16 may be varied as desired to secure proper flow areas, and the opening 20 may be located at any point approaching the top of the pipe segments 26.

In Figs. 4 and 5 is another embodiment of the present invention, which is generally designated by the reference numeral 30. The sprinkler connection 30 is a modified T fitting which comprises a casing 32 having threaded aligned openings 34. A threaded opening 36 extends through the lower portion of the casing 32 which threadedly receives a riser unit 38. The riser unit 38 includes a threaded portion 40, a hexagonal portion 42, and a tubular portion 44 which extends upwardly toward the top of the casing 32. Pipe segments 46 are threadedly

connected into the aligned openings 34, and a pipe segment 48 is threadedly connected into the riser unit 38 and depends therefrom, which receives at its lower end a sprinkler head (not shown). The sprinkler head may be connected directly into the lower part of the riser unit 38 if desired.

The configuration of the casing 32 may be varied as desired to secure proper flow areas, as may the configuration of the riser unit 38. The top of the riser unit 38 should approach the top line of the pipe segments 46 in order to insure that rust and other foreign matter within the main pipe line will not pass into it and thence to the sprinkler head. The riser unit 38 may be cast integral with the casing 32 if desired.

It is manifest that the sprinkler head connections 10 and 30 fulfill the advantages and objects sought therefor. While the present disclosure is directed to a sprinkler head connection for sprinkler systems, the instant novel fitting also finds application in chemical or ore processing, oil refining and similar pipe systems where bleed and take-off lines are taken from the bottom side of main horizontal runs.

It is to be understood that the foregoing description and the accompanying drawing have been given by way of illustration and example. It is also to be understood that changes in form of the elements, rearrangement of parts, and substitution of equivalent elements, which will be obvious to those skilled in the art, are contemplated as within the scope of the present invention which is limited only by the claims which follow.

What is claimed is:

1. A sprinkler head connection for installing a sprinkler head in directly depending relation to a fluid pipe line comprising a casing, means for connecting the casing into a fluid pipe line, means for connecting a sprinkler head to the bottom of the casing, a wall within said casing spaced from the inside thereof and forming therewith a chamber disposed substantially out of the fluid flow path through said connection, and an opening in said inner wall near or above the maximum level of fluid in a connected fluid pipe line communicating said chamber and the area interiorly of said inner wall, the maximum level of fluid in a connected fluid pipe line being the vertical internal diameter of such fluid pipe line, said sprinkler connecting means including an opening through said casing leading from said chamber.

2. A fitting for connecting a pendent line directly into the lower side of a fluid receiving pipe line comprising

a casing, a liquid flow path running through said casing, means for connecting the casing into a fluid receiving pipe line, a wall within said casing out of said liquid flow path, said wall being spaced from the casing and forming therewith a chamber, a portion of said chamber being beneath the liquid flow path of said fitting, an opening in said wall communicating said liquid flow path and said chamber, said opening being at a level near or at the maximum level of liquid in the flow path, and a pendent line connected into said chamber below the top of said fitting.

3. A fitting for connecting a pendent line directly into the lower side of a fluid receiving pipe line comprising a casing, a liquid flow path running through said casing, means for connecting the casing into a fluid receiving pipe line, a wall within said casing out of said liquid flow path, said wall being spaced from the casing and forming therewith a chamber, said chamber comprising an annular space surrounding said liquid flow path, an opening in said wall communicating said liquid flow path and said chamber, said opening being at a level near or at the maximum level of liquid in the flow path, and a pendent line connected into said chamber below the top of said fitting.

25 4. A fitting for connecting a pendent line directly into the lower side of a fluid receiving pipe line comprising a casing, a liquid flow path running through said casing, means for connecting the casing into a fluid receiving pipe line, a wall within said casing, said wall being spaced from the casing and forming therewith a chamber, a portion of said chamber being below the liquid flow path of said fitting, an opening in said wall communicating said liquid flow path and said chamber, said opening being at a level near or at the maximum level of liquid 30 in the flow path, and a pendent line connected into said chamber below the top of said fitting.
